UNITED STATES PATENT OFFICE.

JOSEPH F. O'BRIEN, OF WEST NEW YORK, NEW JERSEY.

AWNNG-ARM.

1,351,341.

Specification of Letters Patent. Patented Aug. 31, 1920.

Application filed June 19, 1917. Serial No. 175,570.

To all whom it may concern:

Be it known that I, JOSEPH F. O'BRIEN, a citizen of the United States, and a resident of West New York, county of Hudson, State 5 of New Jersey, have invented certain new and useful Improvements in Awning-Arms, of which the following is a specification.

This invention relates to improvements in awning arms.

10 By the use of my invention, I produce a simple and inexpensive awning arm, which will be supported solidly on the window frame and will have great rigidity and strength, those parts that are subjected to 15 the most strain having greater strength and all side motion and wobbling of the arms being eliminated. Furthermore, my said arm will, without the use of springs or the like, always normally retain the awning in extended position, the parts of the arm being 20 so correlated and arranged as to cause the weight of the entire arm to exert its pressure on the outer end of the awning and all movement of the outer end of the awning 25 caused by wind or otherwise, will be at once communicated to and taken up by the entire arm.

My invention furthermore embodies certain features of construction, arrangement 30 and combinations of parts which are herein-after more fully set forth and illustrated in the drawings, and will be more particularly pointed out in the appended claims.

In the accompanying drawings in which 35 similar reference characters designate corresponding parts throughout the several views:

Figure 1 is a side elevation of an awning arm or support embodying my invention;

40 Fig. 2 is a front elevation of the device illustrated in Fig. 1;

Fig. 3 is a plan view of the awning arm shown in Fig. 1 in its extended position, the outer member being broken away, and the 45 securing bracket being shown in section.

Referring now to these drawings, 1 indicates the wall of a building, and 3 the canvas of an awning which it is desired to support and guide and which, as illustrated, is 50 adapted to be rolled up on a roller 3^a. The opposite ends of the roller, as shown, are suitably mounted in bearings 3^b on brackets suitably disposed and secured to the wall 1, only one of which brackets is shown and 55 designated 2. Each bracket 2 has, as illustrated, two pairs 4 and 5 respectively of

pivot bearings. Pivoted in the bearings 4 is an outwardly and downwardly inclining base-member 6, comprising, as shown, parallel spaced twin bars 6^a—6^b. To the respective twin members of this base-member 6 are pivoted at their ends two substantially parallel intermediate members 7 and 8 respectively, which members also, as illustrated, comprise parallel twin bars 7^a—7^b 65 and 8^a—8^b respectively, and to the outer ends of both of these members 7 and 8 is pivoted an outer member 9.

It will be apparent that the connection of the intermediate members 7 and 8 at their 70 opposite ends with the base member 6 and outer member 9 provides a parallel disposition of the base and outer members, as well as a parallel disposition of the intermediate members, and this arrangement may be said 75 to form an "articular parallelogram." Suitable means for supporting and guiding the said articular parallelogram intermediate its ends is provided which, as shown, comprises a member pivoted at its inner end 80 in the bearings 5, and at its outer end to the twin bars 8^a—8^b intermediate the ends thereof.

In order to limit the outward extension of the articular parallelogram, I provide 85 an extension 6^c of the base-member, which at a suitable outward limit abuts against the twin bars 8^a—8^b of the arm 8.

It will be obvious from the above, that 90 the tendency of the awning arms will be to extend outwardly and that the entire weight of the several members of the said arms will be caused to press against the outer end of the awning, so that the outer edge of the awning will be prevented from 95 flapping, without the use of springs or the like, and that the slightest movement of the outer edge of the awning will immediately be communicated to all of the members of the arm. Furthermore, it will be 100 obvious that an extremely simple, strong and rigid construction will be provided by the arrangement hereinabove described.

Having described my invention, I claim:

1. An awning support comprising a 105 pair of awning arms at opposite sides of the awning, each side having a base member pivoted at a fixed point to the window frame, two parallel intermediate members pivotally connected to said base member 110 contiguous to the outer end thereof, an outer member connected at one end to the awning

and having a pivotal connection at its opposite ends with the inner of said two parallel members and a connection intermediate its ends with the other of said two parallel members, a supporting member pivoted to one of said intermediate members at one end and to a fixed point on the window frame at the opposite end and means for limiting the extension movement of said members.

10 2. An awning support comprising a pair of awning arms at opposite sides of the awning, each side having a base member pivoted at a fixed point to the window frame, two parallel intermediate members pivotally connected to said base member contiguous to the outer end thereof, an outer member connected at one end to the awning and having a pivotal connection at its oppo-

site end with the inner of said two parallel members and a connection intermediate its ends with the outer of said two parallel members, a supporting member pivoted to one of said intermediate members at one end and to a fixed point on the window frame at the opposite end and an extension on the base member adapted to abut against one of said two intermediate members to limit the extension movement of the awning arm.

20 25 30
In witness whereof I have signed my name to the foregoing specification in the presence of two subscribing witnesses.

JOSEPH F. O'BRIEN.
